UNITED STATES PATENT OFFICE.

HENRI BERNAUDIN, OF COSNE-SUR-LOIRE, FRANCE.

HAND-OPERATED DIESTOCK.

Application filed July 12, 1926, Serial No. 121,960, and in France August 7, 1925.

This invention relates to hand operated die-stocks of the type comprising a carrier or frame for the die or die parts, provided with two operating handles and having means for centering the rod or the like to be screw threaded, such means consisting of two movable guide members with recessed ends adapted to engage the said rod or the like, the said members being suitably attached to the carrier or frame.

According to the present invention the two operating handles of the die-stock are each pivoted to the carrier or frame and so interconnected that when one is moved about its pivot the other is moved about its pivot through a similar angle but in the opposite direction. The centering members are attached to and move with these handles and the arrangement is such that when the handles of the die-stock are operated to cut the screw thread, the recessed ends of the centering members are forced against the rod or the like.

The die is preferably made from a number of parts and adjustable wedge means are provided for adjusting and centering the parts of the die in a manner generally known in die-stocks of the type to which the invention relates.

30 The annexed drawings show, by way of example, one constructional embodiment of the invention, in which

Fig. 1 is a front elevational view of the tool;

35 Fig. 2 is a view looking from beneath in Fig. 1;

Fig. 3 shows a section of the device intended to control the play of the parts of the die;

40 Fig. 4 is a plan view illustrating the play of these parts; and

Fig. 5 is a sectional elevation on the line A—B Fig. 4.

The die-stock consists of a central portion 1 provided at each side with lugs 2, between which are openings 3 adapted for the attachment of arms or handles 4.

45 These arms 4 are extended into and pivotally mounted in position by bearing portions 5, which are pivoted between the lugs 2 and each of them is provided at the side with a lever 6 which levers are hinged together at 7 and embrace the central or middle portion 1. The two arms 4 are therefore dependent upon 50 one another, and small angular movements imparted to one of the arms moves the second

arm through a like angle, the levers 6 being formed springy and moving towards and from the centre of the die-stock to permit the movement. Furthermore a stop pin or projection 8 limits the downward movement of the levers 6 and the upward movement is limited as hereafter explained.

55 Each of the arms 4 operates or controls a guide piece 9 fixed to the bearing portion 5 thereof by means of a screw 10, the extremity 11 of the guide piece being of double bevel form. The extremities of these two guide pieces 9 are adjusted very accurately and at an absolutely exact distance from the centre of the parts 12 of the die so as to be able to simultaneously be forced against the rod to be screw threaded, from diametrically opposite sides in order to centre it with respect to the axis of the stock during the whole time that the work 70 is being conducted. The upward movement of the levers 6 is limited by the extremities 11 of the pieces 9 coming into contact with the rod or the like.

75 The central or middle portion 1 is provided with a perforation 13 furnished with a ledge 14 adapted to receive the die portions 12, which are three in number. These portions, as shown in Figs. 4 and 5, are provided around their periphery with a groove 15 in which is 80 located a helical spring which keeps them coupled together. The helical spring is not shown on the drawings but is provided with a loop or other portion through which the pointed rod of a regulating device hereafter 85 described, is adapted to project. Two of the die portions 12 are provided with a channel constituting when they are assembled together a slightly conical perforation 16 in which engages the pointed rod of the regulating device 90 shown at Fig. 3. This device includes the pointed rod 17 furnished with a milled head and adapted to screw into the clamp or holder 18 located in a recess provided in the central or middle portion 1 of the stock. This clamping piece 18 is provided with an incurved portion adapted to fit exactly against the die portions 12. 95

19 is a locknut screwing into a screw threaded perforation in the middle portion 1 and enabling the device to be locked after regulating the space between the three die portions 12 according to requirements.

100 After these die portions 12 have been placed in their holder 13, the pointed rod 17 is screwed in until its extremity penetrates into the slightly conical hole 16. In this way the diameter of the screw thread can be varied by 105

separating more or less two of the parts 12, which parts are restored to position by the helical spring located in the channel 15 when it is desired to obtain a thread of the smallest possible diameter.

The parts 12 being placed in their holder or casing, the pointed rod 17 enables these latter to be separated and the clamping piece 18 controlled by the locking screw 19 enables 10 the three parts to be brought together to diminish the diameter of the screw threaded element.

The die itself may consist of any suitable 15 number of blocks or parts 12 (three in the case shown). The coupling together of these parts is effected by engaging parts 20.

The action of the device is as follows. The rod to be screw threaded is held in a vise or the like in the ordinary manner and the die 20 is placed on the end thereof. At the commencement of the operations the handles 4 are pulled upwards to move about their pivots 5 as far as permitted by the stop 8. This causes the extremities 11 of the guide pieces 25 9 to separate as far as possible and remain free of the rod to be screw threaded which is located between them. Now by pressing downwards on the handles 4, they turn to a slight extent on their pivots 5 and the extremities 11 of the guide pieces 9 are caused 30 to bear against the rod to be screw threaded. It will thus be seen that this rod by the extremities 11 supports the tool evenly with relation to the rod and provides a steady 35 self-centering device enabling the die portions to cut an accurate thread.

What I claim and desire to secure by Letters Patent of the United States of America is:—

1. A hand operated die-stock comprising in combination a carrier for the die, a die supported by said carrier, two handles pivoted to the carrier at diametrically opposite positions with respect to the die, the axes of the pivots being disposed at right angles to the axis of the die, interconnecting means 45 between the pivoted handles for ensuring equal angular movement of the handles in opposite directions, and guide members attached to the handles, the extremities of said 50 guide members being disposed opposite each other and at equal distances from the axis of the die.

2. A hand operated die-stock comprising in combination a carrier for the die, a circular stepped opening in the carrier, a die formed from a plurality of sections located in said stepped opening, means supported by the carrier for adjusting the sections of the die, two handles pivoted to the carrier at diametrically opposite positions with respect to the die, the axes of the pivots being disposed at right angles to the axis of the die, interconnecting means 55 between the pivoted handles for ensuring equal angular movement of the handles in opposite directions, and guide members attached to the handles, the extremities of said 60 guide members being disposed opposite each other and at equal distances from the axis of the die. 65

In witness whereof I affix my signature.
HENRI BERNAUDIN. 70
